FIG. 6.

UNITED STATES PATENT OFFICE.

WILLIAM F. J. WOLTJES, OF LONG BEACH, CALIFORNIA.

COMBINATION TENT CONSTRUCTION.

Application filed June 2, 1927. Serial No. 196,009.

This invention relates to a tent.

It is aimed to provide a novel construction capable of various uses such as enabling the human body to be concealed from observation while being subjected to the action of the sun's rays, as a store or the like along a highway or as a shelter for an automobile.

One particular object is to provide a structure which may be readily assembled and 10 disassembled and folded into compact form to facilitate transportation.

A further object is to provide a novel tent in which the sides may be elevated or lifted if desired, at least two sides, and the tent be 15 rigidified and held in such a manner that it cannot be readily blown down.

Various additional objects and advantages will become apparent from a consideration 20 of the description following taken in connection with accompanying drawings illustrating an operative embodiment.

In said drawings:

Figure 1 is a perspective view showing the tent used for sleeping purposes;

25 Figure 2 is a perspective view showing the tent with two sides thereof raised to primarily provide a place of shade;

Figure 3 is an elevation of one of the tent poles;

30 Figure 4 is a vertical sectional view through one of the tent poles, with the sections thereof parted;

Figures 5 and 6 are elevations of connecting poles used for the sides and which views 35 are taken at right angle to each other;

Figure 7 is a detail view of the means for securing the extended wall supporting rods to the sustaining poles.

Referring specifically to the drawings, the 40 tent may be made of any desired size, and of any appropriate shape, for instance substantially square as in Figure 1.

At the corners and between the corners, if desired, poles 10 of an appropriate construction are used. Such poles may be of wood 45 or metal as preferred, and preferably are in sections 11 and 12 adapted for detachable connection as by means of a socket 13 carried by the sections 11 which telescopically

50 and frictionally receive a tenon or projection 14 of the other section. The sections 11 serve as anchor sections and may be driven into the ground to which end their lower extremities 15 are sharpened as shown.

55 The vertical walls of the tent are each

preferably of a size to cover the space between two adjacent poles 10, such walls being for instance of canvas and illustrated as at 16. The canvas of the side walls 16 may be plain or ornamented and supported by 60 engaging hooks 21 screwed into the sections 12 of the poles.

In order to appropriately brace the structure, brace members 21 are used which may be wires, cords, chains, or the like which are 65 attached at their upper ends to screw eyes 22 fastened into the sections 12 above the hooks 21 and which at their lower ends carry anchors 23 adapted to be driven into the ground.

70 The walls 16 are preferably at two sides adapted to be lifted, as suggested in Figure 2, such walls may carry at their upper and lower marginal edges, rods 24 connected to such walls by hooks or the like 25 and having attaching elements 26 at their ends consisting of plates provided with eyelets 27 adapted to engage hooks 21 screwed to adjacent poles 10. The plates 26 occupy a bifurcation in the ends of the rods 24 and 80 fastened therein by bolts or rivets as at 29.

75 The device may be used without any roof whatever thus a person may be enclosed thereby even in the nude, so as to be subjected to the benefit of the sun's rays in the 85 treatment of certain diseases or ailments, and within the tent, the patient may have desirable appurtenances such as a chair, cot, or the like.

80 Stops 34 are provided on poles 10 and are 90 in the form of contractile rubber rings or collars which surround and grip the sections 12 above the eyelets 22 and are adjustable longitudinally of such sections.

85 A water-proof cover 37 is provided and is 95 preferably of water-proof canvas or the equivalent and at its corners is provided with eyelets 39 adapted to engage the poles 10 and to be sustained in elevated position by stops 34.

100 The device when disassembled may be rolled or packed in relatively compact form and form but a small bundle or bundles so as to be readily portable.

105 It is to be understood that the tent or combination may be used generally as a knock down and portable structure. A particular advantage of the adjustability of rings 34 is that certain of them, for instance those at one side of a tent may be arranged higher 110

than at the other side of the tent to substantially incline the top of the tent so as to readily shed water.

Various changes may be resorted to provided they fall within the spirit and scope of the invention.

What is claimed is:—

1. In a tent, poles to support the walls thereof, an element adjustable along said poles, and a roof supported by the poles and controlled as to elevation by said elements,

said elements consisting of contractile bands.

2. A tent having poles, hooks on said poles, walls suspended on said hooks, means to connect the walls to each other, eyelets on said poles above the hooks, brace means attachable to the eyelets, a roof having openings through which the poles extend, and longitudinally adjustable elements on the poles to determine the position of the roof. 15 20

In testimony whereof I affix my signature.

WILLIAM F. J. WOLTJES.
